United States Patent Office

Des. 188,226

Patented June 14, 1960

188,226

AIRPLANE

Robert D. Jones, Charlestown, Mass., and Lawrence W. Emerson, Scarsdale, N.Y. (both of U.S.S. Tanner (AGS-15), F.P.O.)

Filed Sept. 11, 1959, Ser. No. 57,513

Term of patent 14 years

(Cl. D71—1)

Figure 1 is a top perspective view of an airplane showing my new design;

Figure 2 is a front elevational view thereof; and
Figure 3 is a side elevational view thereof.

We claim:

The ornamental design for an airplane, as shown.
